UNITED STATES PATENT OFFICE.

SAMUEL SNELLENBURG, OF PHILADELPHIA, PENNSYLVANIA.

RECIPROCATING PROPELLER FOR VESSELS.

SPECIFICATION forming part of Letters Patent No. 415,584, dated November 19, 1889.

Application filed August 13, 1889. Serial No. 320,605. (No model.)

To all whom it may concern:

Be it known that I, SAMUEL SNELLENBURG, a citizen of the United States of America, residing at Philadelphia, in the county of Philadelphia and State of Pennsylvania, have invented certain new and useful Improvements in Reciprocating Propellers for Vessels; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to certain new and useful improvements in reciprocating or vibrating propellers for vessels.

The object of the invention is to provide a propelling means for vessels which consists of a sliding or reciprocating frame connected with actuating means—as the piston of an engine—the said frame being mounted on guides and carrying a series of floats or paddles which are mounted in the sliding frame to contact with transverse bars or stops carried by vertically-moving bars, said bars engaging with a rod for raising the same, so that the paddles will be permitted to move past the stops when it is desired to reverse the action of the floats or paddles, the whole being mounted in suitable frames secured to the vessel between the keels thereof and also between the twin propellers, as will be herein-after more fully set forth, and particularly pointed out in the claims.

In the accompanying drawings, Figure 1 is a side view, partly in section, of my improved reciprocating propeller, showing its application to a vessel. Fig. 2 is a vertical longitudinal sectional view. Fig. 3 is a rear elevation. Fig. 4 is a detail view of one of the paddles or floats.

A refers to the hull of the vessel, which may be constructed in the usual manner, though it is preferably provided with two keels at its rear portion and with twin screws or propellers. In front of the twin screws or propeller-blades and between the same, in the arch formed in the hull between the keels, are secured by any suitable means two frames B B, having open ends and bottom, the front

ends of the side walls being inclined, as shown. It is immaterial as to how these frames are secured to the vessel, as they may be built to suit the special construction of the vessel, though it is essential that the supporting-frames should be rigid and provided with vertical sides B'. These sides pieces, which in practice are four in number, two 60 casings being used upon a vessel, are provided with inwardly-extending guide-rails b and b', the upper guides having their inner edges bent over to extend downwardly, while the lower ones extend upwardly. These 65 guides serve as direct supports for the reciprocating frames C.

The reciprocating frames C are made up of side pieces C', to the outer edges of which are rigidly secured strips c and c', the upper 70 and lower edges of which extend in opposite directions to retain in place anti-friction rollers d, upon which the frames C slide. The side pieces C' of the reciprocating frame C are rigidly connected to each other by transverse plates e e, e', and f, as well as the cross-bars f', upon which the paddles or floats are hinged. The transverse bars f' are preferably made of flat or rectangular metal, and their edges are beveled to offer but little resistance to the water, and flat bars with beveled edges can be substituted for the rods f f where desired. The rod connecting with the actuating mechanism or piston-rod is bolted or otherwise secured to the transverse bars 85 e'. The transverse bars f' have their edges cut away at suitable points to provide rounded portions, upon which are hinged the paddles or floats F, said paddles being made of metal or wood re-enforced with metal when it is 90 desired to provide buoyancy, and when such are employed the rests or stops f may be dispensed with. The floats F ordinarily rest upon the rods or supports f when the propeller is being moved to an operative position, and it will be observed that these rods or supports are located slightly above the plane of the bars f', so that the floats will be held at a proper angle, which is of about one inch to the foot, and will catch against the 100 water, so as to be immediately raised to a vertical position when the frames C are moved either backward or forward.

G refers to the vertical bars secured to the

sides C' by bolts which pass through slots g, and these vertically-moving bars have offsets h, to which are secured transverse rods i, with which the ends of the blades contact. The 5 upper ends of these vertically-moving bars G are connected by transverse pieces g', upon which are secured straps g², and within these straps plays a sliding bar I, supported by means of the depending loops or straps j, adjacent to which the under edge of the bar I is cut away at two different points to provide the recesses i', which recesses are close to each other to provide a short intermediate space. The horizontally-sliding bar I and 10 vertically-sliding bars G provide a means for reversing the floats, so that the vessel can be propelled either backward or forward. The loops or straps which maintain the bar I in position are beveled or shaped to correspond 15 with the configuration of the recesses i'. To reverse the action of the paddles, but one stroke of the reversing bar or lever is necessary, as by throwing the said lever it will move the bar I to elevate the frame G and 20 permit the blades to pass under the stops i, after which the frame G drops by reason of the other recess i' fitting over the loop j, which operation will cause the paddles to exert an opposite pressure upon the water to 25 propel the vessel in an opposite direction. When desired the sliding bar I can be supported within the loops j at the flat space between the angular recesses i', which will retain the frame G in an elevated position and 30 allow the paddles to have free movement backward and forward, thus rendering them inoperative. It will be observed that the blades or paddles are very narrow in proportion to their length, and when they are so 35 shaped they will be thrown quickly in position; and a larger number of paddles may be used than are shown in the drawings. The paddles are provided with loops, as shown in Fig. 4, which form the hinges, so that they 40 can be readily attached and detached. When 45 in operation one of the sets of paddles may be set to propel the vessel forward, while the other set acts in the reverse direction, which operation will assist in bringing the vessel 50 about.

Heretofore it has been proposed to provide propellers for vessels which consist of two or more reciprocating paddles which have either been pivoted centrally or hung upon pivotal 55 supports. Such construction in practice has proved objectionable for many reasons which it is deemed unnecessary to herein mention. It has also been proposed to pivot the floats near their centers and provide stops which 60 engage with the lower portions of the floats, so that the same floats may be used for propelling the vessel either backward or forward.

In practice I propose to employ a number 65 of floats in each frame or casing arranged in both horizontal and vertical series, and said

floats are pivoted at their ends, so that those on the reverse stroke will incline upwardly. By this construction and arrangement many advantages are attained, among which may 70 be mentioned, first, that the blades act quickly to be brought into an operative position; second, should there be any obstructions in the water they will either slide over the floats or contact with the rigid transverse bars, so as 75 not to interfere or obstruct the operation of the paddles; also, by providing a large number of narrow paddles in a vertical series they will have more area and will act more quickly and effectively upon the water, and greater 80 power is obtained from the use of a series of paddles than from one paddle of the same area, and there is less strain upon the engine and greater power developed.

This device is adapted to be used in connection with twin propellers located on each side of the stern-post, and by properly gearing the parts the same engine or motor can be used for operating the reciprocating propellers as is used for rotating the screws. 85

In order to give a uniform motion to the vessel, two frames are used, one being geared to move forward while the other is moving aft.

Having thus described my invention, what I 95 claim is—

1. In a reciprocating propeller for vessels, the combination of a suitable frame having horizontal guideways, a sliding frame mounted on said guideways and provided with a 100 series of transverse bars upon which are hinged floats or paddles, vertically-sliding bars carrying transverse rods or stops against which the ends of the blades abut, so as to be held in a vertical position, and a notched 105 bar supported in hangers having V-shaped portions upon which said notches lie for vertically moving said sliding bars, so that the floats may pass under the transverse bars or stops carried thereby, substantially as shown, 110 and for the purpose set forth.

2. The combination, in a reciprocating propeller, of a casing having an open bottom and ends, sliding frames carrying a number of paddles or floats arranged in vertical 115 or horizontal series, said floats or paddles being hinged to rigid cross-bars, bars f and movable bars carried by vertically-movable bars G, and means for adjusting said bars, the sliding frames being mounted upon interlocking ways having anti-friction rollers, substantially as shown, and for the purpose set forth.

3. The combination of two or more sliding frames carrying vertically-adjustable bars 125 having stops thereon, said bars having slots for limiting the vertical movement thereof, a series of hinged paddles carried by the frames, so as to swing upwardly upon the said pivots, a notched bar I, supported in 130 loops j, said bar passing beneath transverse bars attached to the vertically-sliding bars

G, so that said bars G may be raised when the bar I is moved rearwardly to permit the paddles to swing under the stops i, substantially as shown, and for the purpose set forth.

5 4. The combination, with a sliding frame carrying a series of paddles, of a vertically-moving frame G, and a sliding bar I, for operating the frame G, said bar having adjacent to its support two notches to engage with the loops j, so that when the bar I is moved the frame G will be raised and lowered, substantially as described.

10 5. The combination, with the sliding frame carrying a series of hinged paddles and permanent or immovable stops therefor, of a ver-

15 tically-moving frame G, carrying stops or cross-bars, and loops through which passes the sliding bar I, said bar being suspended in loops j, the cross-pieces of which are angular, said bar I having two sets of notches to engage with the loops j, and a lever for operating said bar, the parts being organized substantially as set forth.

20 In testimony whereof I affix my signature in presence of two witnesses.

SAMUEL SNELLENBURG.
